ALTERNATING CURRENT RELAY

Lloyd D. Auten, Fredericktown, Ohio, assignor to The Hartman Electrical Manufacturing Company

Application May 29, 1953, Serial No. 358,500

17 Claims. (Cl. 200—91)

The invention relates in general to electromagnetic structures and more particularly to relays operable on alternating current wherein two separate windings are provided on the core and energized at a phase angle preferably ninety degrees and operating on a pivoted armature, which has exerted thereon a substantially constant torque through a complete cycle of the energizing voltage.

The prior art alternating current relays have previously used a core structure wherein there was established in the core two separate fluxes that were out of phase. Generally these two separate fluxes are a main flux and a lagging auxiliary flux caused by a shading coil. Such shading coils do shift the flux phase relationship, however, to be effective they require intimate contact between the armature and pole face, which destroys accurate control of the voltage drop out point, and also they are undesirable and uneconomical in that they cause a power loss in the shading coil and cause increased heating of the core and windings.

An object of the invention is to provide an alternating current relay which is free of chatter or hum without using any shading coils.

Another object of the invention is to provide a relay having a balanced armature construction so that the contacts operated by the relay armature will not be affected by acceleration, vibration, or physical shock.

Still another object of the invention is to provide a relay construction which combines two or more magnetic forces through a common armature.

Still another object of my invention is to provide an electromagnetic structure utilizing two coils to achieve two magnetomotive forces which are to some extent out of phase to establish a unidirectional torque on a rotatable armature.

Another object of the invention is to provide an electromagnetic structure for use on alternating currents which has greater torque and hence permits a small structure for a given magnetic pull.

Still another object of my invention is to provide a magnetic structure which may be applied to very small as well as very large designs.

Another object of my invention is to provide an alternating current relay which has freedom from chatter or hum caused by the alternations of the frame so that the armature need not actually contact the pole pieces and hence inaccurately controlling the voltage drop-out point of the relay contacts, instead, accurate control of the voltage drop-out point of the relay contacts may be obtained.

Another object of my invention is to provide a relay having constant torque on the relay armature and constant pressure on the electrical contacts throughout a 360-degree cycle of the energizing voltage to obtain low contact resistance.

Other objects and a fuller understanding of this invention may be had by referring to the following description and claims, taken in conjunction with the accompanying drawings, in which:

2

Figure 1 is a top view of a relay embodying the principles of the invention;

Figure 2 is a sectional view taken on the line 2—2 of Figure 1;

5 Figure 3 is a sectional view taken on the line 3—3 of Figure 2;

Figure 4 is a sectional view taken on the line 4—4 of Figure 3;

10 Figure 5 is a partial view similar to Figure 4 and showing the armature in a magnetically energized position;

Figure 6 is an electrical schematic diagram showing energization from three phase;

Figure 7 is a schematic diagram showing an alternative energization method; and

15 Figure 8 is a schematic diagram showing energization from single phase or direct current.

The Figures 1 to 4 show the preferred form of the invention which has been embodied in an alternating current relay 11. The relay 11 has frame 12, core 13, windings 14, and an armature 15. The frame comprises the first, second, third, and fourth insulating blocks 16, 17, 18, and 19. The blocks 16, 17, and 18 are fastened together by rivets 20 with the core therebetween. The Figure 4 best shows the core 13, and it comprises a first core portion 21 and a second core portion 22. Each of these core portions is generally U-shaped. The first core portion 21 has a long leg 23 and a short leg 24. Similarly, the core portion 22 has a long leg 25 and a short leg 26. The legs 23 to 26 each have inwardly extending feet 27 to 30, respectively. All feet are generally parallel and spaced and extend into magnetic coupling arrangement with the armature 15. The pole faces of all feet 27 to 30 preferably lie in parallel planes. A first coil 31 is disposed on the core portion 21 and a second coil 32 is disposed on the core portion 22.

35 The armature 15 is generally elongated and magnetic and has first and second flat faces 35 and 36. The armature is fixedly attached to a shaft 37 which is journaled in a bearing 38 in the block 16 and in a bearing 39 in the block 19.

40 The shaft 37 carries an insulator disk 41 for rotation therewith. A contact spring 42 extends generally radially from one side of the disk 41 and has contacts 43 thereon for cooperation with oppositely disposed fixed contacts 44 and 45. These contacts 44 and 45 are adjustable, as shown by the mounting screws 46. An insulator sleeve 33 surrounds the shaft 37 between the disk 41 and the armature 15 to insulate the shaft from a flexible lead 34 extending to the contact spring 42. A resilient strip 47

45 extends from the disk 41 generally diametrically opposite the contact spring 42. A coil spring 48 extends between the outer end of the resilient strip 47 and an adjustable screw 49 mounted on the frame 12. A rotatable screw 50 is rotatably carried in the block 19 and has a flat 51 thereon to act as an adjustable stop for the resilient strip 47. It will be noted that the entire movable armature assembly is symmetrical and pivoted at the center of gravity and that this symmetry even includes the disk 41 with the resilient strip 47 and contact spring 42 thereon.

50 This mounting at the center of gravity assures that acceleration, shocks, and vibration will not affect the position of the armature 15 relative to the frame 12, which is of particular benefit in many applications. The block 19 is fastened to the blocks 16, 17 and 18 by any suitable means such as the bolts 52. The armature 15 has a reduced width at the ends to permit arcuate movement as shown in Figures 4 and 5. Figure 5 shows the position of the armature when the core 12 is magnetized, and in this position, the faces 35 and 36 are generally parallel to the pole faces of the feet 27 and 30. A non-magnetic abutment 53 is adjustably carried on a core bracket 54, with this abutment 53 preventing actual contact of the

55

60

65

70

armature faces 35 or 36 with the pole faces of the core. This prevents sticking of the armature to the pole faces by residual magnetism after de-energization of the windings 14, and thus an accurate control of the voltage drop-out point may be obtained.

The Figure 6 shows a method of energization of the relay 11. Coils 55, 56 and 57 represent the three phase windings of an alternator or transformer. The windings 31 and 32 of the relay 11 are energized from such a three phase source with the coil 31 connected across the extremities of the coils 56 and 57 and the coil 32 connected across the coil 55. This will place a higher voltage on winding 31, hence preferably the winding 32 will have the square root of three times the number of turns on winding 31 so that each winding will have the same number of ampere turns. The energization system of Figure 6 will establish voltages 90 degrees out of phase on the windings 31 and 32 and these windings establish magnetomotive forces which are likewise 90 degrees out of phase. As best seen in Figure 4, each of these windings 31 and 32 establish magnetomotive forces in separate magnetic circuits.

The magnetomotive force of each of the windings 31 and 32 operates by means of the feet 27 to 30, on opposite longitudinal sides of center of the armature 15 and on opposite lateral sides of the armature.

The flux from the winding 31 will thread the core 21, passing through the foot 27, the right half of armature 15 and the foot 28. Similarly, the flux from the coil 32 will thread the core 22 through the foot 30, the left half of the armature 15 and the foot 29. Each of these fluxes will establish a torque on the armature which is clockwise as viewed in Figure 4. This clockwise torque is resisted by the coil spring 48, which maintains the armature 15 in the position shown in Figure 4 when the relay is de-energized. Upon energization, the force of the flux causes rotation of the armature to the position shown in Figure 5. The force or torque exerted on the armature 15 is proportional to the square of the flux, which is proportional to the square of the applied voltage as long as the operation of the core is maintained below the knee of the saturation curve. This force, being proportional to the square of the applied voltage, is thus a double frequency component and with the windings 31 and 32 ninety degrees out of phase, the total force or torque on the armature is uniform throughout a complete 360-degree cycle. This completely eliminates chattering of hum and maintains an even contact pressure on the contacts 43 and 45. Also with this uniform and constant torque, the voltage drop-out setting of the relay may be accurately established without the necessity of having the armature actually contact the pole faces to be held in place by the residual magnetism. Since the armature does not contact the pole faces, there is not the chatter and hum generally associated with alternating current relays.

Another means of obtaining a ninety degree phase shift is to use one of the various means for changing between three phase and two phase, other than the one shown in Figure 6. The Scott connection of transformers is one such method for obtaining two voltages ninety degrees apart in phase from a three phase source.

The Figure 7 shows an alternative arrangement for energization from a three phase source with the winding 32 energized across the extremities of the windings 55 and 57 and the winding 31 energized across the extremities of the windings 56 and 57. This will establish a phase difference of 60 degrees between the windings 31 and 32 which will give satisfactory operation under many different conditions. With 60-degree phase displacement, there is some variation in the torque on the armature 15; however, this phase displacement is generally greater than that obtainable by the use of shading coils and hence this construction produces an

alternating current relay which has performance equal to or better than most prior forms of alternating current relays.

The Figure 8 shows a circuit for energization of the windings 31 and 32 from a voltage source represented by lines 58 and 59. The lines 58 and 59 may carry alternating current or direct current. With operation on alternating current, impedances 60 and 61 may be used as phase shifting devices. Either one or both of these impedances may be used, and they may be used in various combinations of resistive, inductive, or capacitive to obtain phase shift in the well-known manner. A phase shift of at least 45 degrees is desirable in order to reduce the chattering and hum and to obtain more nearly uniform contact pressure and drop-out settings, however any degree of phase shift will give an overlapping of magnetomotive forces from each of the two windings, hence at all times there will be a torque exerted on the armature by the two windings in combination.

The relay 11 may be operated on direct current such as by a circuit as in Figure 8 without the use of any series or parallel impedances. The relay will operate quite satisfactorily on direct current, because the windings 31 and 32 will each produce equal and clockwise torques on the armature 15.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. An electromagnetic structure comprising, a frame; an armature pivoted to said frame, first and second discrete-permeable cores fixedly attached to said frame and each being magnetically coupled to said armature at least in one position of said armature for first and second magnetic circuits, means to urge said armature clockwise, first and second winding means on said structure to establish first and second varying in time magnetomotive forces in said cores of different phase, and said cores being physically disposed relative to said armature whereby said first and second magnetomotive forces each establish counter-clockwise torques at the same time in said armature of a value sufficient to overcome said urging means.

2. An electromagnetic structure comprising, a frame; a permeable armature pivoted substantially at the center of gravity thereof to said frame, permeable core means fixedly attached to said frame and magnetically coupled to said armature at least in one position of said armature for first and second magnetic circuits, said armature having two long sides defining a length dimension, said core means extending on opposite longitudinal sides of said pivot center, means to urge said armature clockwise, first and second winding means on said structure to establish first and second alternating magnetomotive forces in said core means of different phase, and said core means being physically disposed relative to said armature whereby said first and second magnetomotive forces establish counter-clockwise torques in said armature of a value sufficient to overcome said urging means and to maintain continuously a counter-clockwise torque on said armature throughout a three hundred sixty degree cycle of said alternating magnetomotive forces.

3. An electromagnetic structure comprising, a frame; a permeable armature pivoted substantially at the center of gravity thereof to said frame, first and second discrete-permeable cores fixedly attached to said frame and magnetically coupled to said armature, said armature having

two long sides defining a length dimension, said cores each extending on opposite longitudinal sides of said pivot center, means to urge said armature clockwise, said armature with said cores establishing first and second magnetic circuits, first and second winding means on said first and second magnetic circuits to establish first and second alternating magnetomotive forces in said core substantially ninety degrees out of phase, and said cores being physically disposed relative to said armature whereby said first and second magnetomotive forces establish substantially equal counter-clockwise torques in said armature of a value sufficient to overcome said urging means and to maintain a substantially constant counter-clockwise torque on said armature throughout a three hundred sixty degree cycle of said alternating magnetomotive forces.

4. An electromagnetic structure comprising, a frame, an armature pivoted to said frame, first and second discrete permeable cores fixedly attached to said frame and each being magnetically coupled to said armature, said armature in one position thereof completing at the same time substantially closed first and second magnetic circuits in said first and second cores, respectively, first and second winding means on said first and second magnetic circuits to establish first and second alternating magnetomotive forces in said first and second cores, respectively, of different phase, means to urge said armature clockwise, and said cores being physically disposed relative to said armature whereby said first and second magnetomotive forces each establish counter-clockwise torques at the same time in said armature of a value sufficient to overcome said urging means.

5. An electromagnetic structure comprising, a frame, a permeable armature pivoted to said frame, a permeable core fixedly attached to said frame and having first and second portions magnetically coupled to said armature, said armature in one position thereof completing substantially closed first and second magnetic circuits for said first and second core portions, respectively, first and second winding means on said first and second magnetic circuits to establish first and second alternating magnetomotive forces in said first and second core portions at least sixty degrees out of phase, means to urge said armature in one rotational direction and said core portions being physically disposed relative to said armature whereby said first and second magnetomotive forces establish substantially equal torques in said armature in the same rotational direction and opposite to said one rotational direction of a value sufficient to overcome said urging means and to maintain a torque on said armature in said opposite rotational direction throughout a three hundred sixty degree cycle of said alternating magnetomotive forces.

6. An electromagnetic structure comprising, a frame, a permeable armature pivoted to said frame, a permeable core fixedly attached to said frame and having first and second portions magnetically coupled to said armature, said armature in one position thereof completing substantially closed first and second magnetic circuits for said first and second core portions, respectively, first and second winding means on said first and second magnetic circuits to establish first and second alternating magnetomotive forces in said first and second core portions substantially ninety degrees out of phase, means to urge said armature clockwise, and said core portions being physically disposed relative to said armature whereby said first and second magnetomotive forces establish substantially equal counter-clockwise torques in said armature of a value sufficient to overcome said urging means and to maintain a substantially constant counter-clockwise torque on said armature throughout a three hundred sixty degree cycle of said alternating magnetomotive forces.

7. An electromagnetic structure comprising, a frame, a permeable armature pivoted substantially at the center

of gravity thereof to said frame, a permeable core fixedly attached to said frame and having first and second portions magnetically coupled to said armature, said armature having two long sides defining a length dimension, each of said first and second core portions extending on opposite longitudinal sides of said pivot center and extending on opposite lateral sides of said armature, means to urge said armature clockwise, said armature in one position thereof completing substantially closed first and second magnetic circuits for said first and second core portions, respectively, first and second winding means on said first and second magnetic circuits to establish first and second alternating magnetomotive forces in said first and second core portions substantially ninety degrees out of phase, and said core portions being physically disposed relative to said armature whereby said first and second magnetic forces establish substantially equal counter-clockwise torques in said armature of a value sufficient to overcome said urging means and to maintain a substantially constant counter-clockwise torque on said armature throughout a three hundred sixty degree cycle of said alternating magnetomotive forces.

8. An electromagnetic structure comprising, a frame, a generally U-shaped core on said frame, an armature pivotally mounted to said frame, first and second feet on said core extending inwardly toward said armature and spaced different distances from said pivot, said two feet being disposed on opposite sides of said armature, first and second winding means disposed on said structure, and means for energizing said two winding means from a varying voltage source with a phase displacement therebetween to establish in said armature two separate fluxes with a phase displacement therebetween in accordance with said energization phase displacement.

9. An electromagnetic structure comprising, a frame, first and second magnetically separate cores on said frame, an armature pivotally mounted to said frame at the center of gravity of said armature, said armature and cores so constructed that said armature in one position thereof completes a magnetic path for both said cores, separate winding means disposed on said cores, and means for energizing said winding means form an alternating current source for substantially equal ampere turns at a phase displacement of at least sixty degrees therebetween.

10. An electromagnetic structure comprising a frame, first and second permeable core portions generally U-shaped with first and second legs on said frame, a symmetrical armature pivotally mounted to said frame, first and second permeable feet on said first and second legs, respectively extending inwardly toward said armature, the first foot of said first core portion being adjacent the second foot of said second core portion and on the same side of said armature, said two feet on each core portion being disposed on opposite sides of said armature, each of said first feet being the same distance from said pivot point, each of said second feet being the same distance from said pivot point, winding means disposed on said first and second core portions, respectively, and means for energizing said winding means from an alternating current source for generally equal ampere turns at a phase displacement of at least forty-five degrees.

11. An electromagnetic structure comprising a frame, first and second permeable core portions generally U-shaped with first and second legs on said frame, a permeable armature pivotally mounted to said frame substantially at the center of gravity of said armature, first and second permeable feet on said first and second legs, respectively, extending inwardly toward said armature, the first foot of said first core portion being adjacent the second foot of said second core portion and on the same side of said armature, said two feet on each core being disposed on opposite sides of said armature, each of said first feet being the same distance from said pivot point, each of said second feet being the same distance from

said pivot point, first and second coils disposed on said first and second cores, respectively, and means for energizing said coils from an alternating current source for substantially equal ampere turns at a phase displacement therebetween, whereby for any and all rotational positions of said armature there exists a generally uniform torque on said armature throughout a complete cycle of said alternating current voltage.

12. An electromagnetic structure comprising a frame, first and second permeable core portions generally U-shaped with first and second legs on said frame, a permeable symmetrical armature pivotally mounted to said frame at the center of gravity of said armature, first and second permeable feet on said first and second legs, respectively, extending inwardly toward said armature, the first foot of said first core portion being adjacent the second foot of said second core portion and on the same side of said armature, said two feet on each core portion being disposed on opposite sides of said armature, each of said first feet being the same distance from said pivot point, each of said second feet being the same distance from said pivot point, said armature in one rotational limit adapted to lie closely adjacent the ends of all said feet, first and second coils disposed on said first and second core portions, respectively, and means for energizing said coils from an alternating current source for substantially equal ampere turns at a phase displacement of substantially ninety degrees therebetween, whereby for any and all rotational positions of said armature there exists a substantially constant torque on said armature throughout a complete cycle of said alternating current voltage.

13. An electromagnetic structure comprising a frame, first and second discrete permeable cores generally U-shaped with long and short legs on said frame, a permeable elongated symmetrical armature pivotally mounted to said frame at the center of gravity of said armature, first and second permeable feet on said long and short legs, respectively, extending in parallel and spaced relationship inwardly toward said armature, the first foot of said first core being adjacent the second foot of said second core and on the same side of said armature, and said two feet on each core being disposed on opposite sides of said armature, each of said first feet being the same distance from said pivot point, each of said second feet being the same distance from said pivot point, said armature in one rotational limit adapted to lie closely adjacent the ends of all said feet, first and second coils disposed on said first and second cores, respectively, and means for energizing said coils from an alternating current source for substantially equal ampere turns at a phase displacement of substantially ninety degrees therebetween, whereby for any and all rotational positions of said armature there exists a substantially constant torque on said armature throughout a complete cycle of said alternating current voltage.

14. An electromagnetic structure comprising a frame, first and second discrete permeable cores generally U-shaped with long and short legs on said frame, all said long and short legs being parallel, a permeable elongated symmetrical armature pivotally mounted to said frame at the physical center and center of gravity of said armature, first and second permeable feet on said long and short legs, respectively, extending in parallel and spaced relationship inwardly toward said armature, the first foot of said first core being adjacent the second foot of said second core and on the same side of said armature, said two feet on each core being disposed on laterally opposite sides of said armature, the two feet on each core being on longitudinally opposite sides of center of said armature, each of said first feet being the same distance from said pivot point, each of said second feet being the same distance from said pivot point, said armature in one rotational limit adapted to lie closely adjacent the ends of all

5 said feet, means to urge said armature away from said one rotational limit, first and second coils disposed on said first and second cores, respectively, and means for energizing said coils from an alternating current source for substantially equal ampere turns at a phase displacement of substantially ninety degrees therebetween, whereby for any and all rotational positions of said armature there exists a constant torque on said armature throughout a complete cycle of said alternating current voltage.

15. An electromagnetic structure comprising a frame, a permeable armature pivoted substantially at the center of gravity thereof to said frame, a permeable core fixedly attached to said frame and having first and second portions magnetically coupled to said armature, said armature having two long sides defining a length dimension, said core extending on opposite longitudinal sides of said pivot center and extending on opposite lateral sides of said armature, means to urge said armature clockwise, said armature in one position thereof completing substantially closed first and second magnetic circuits through said first and second core portions, respectively, first and second winding means on said first and second magnetic circuits to establish first and second alternating magnetomotive forces in said first and second core portions substantially ninety degrees out of phase, and said core portions being physically disposed relative to said armature whereby said first and second magnetomotive forces establish substantially equal counterclockwise torques in said armature of a value sufficient to overcome said urging means and to maintain a substantially constant counterclockwise torque on said armature throughout a three hundred sixty degree cycle of said alternating magnetomotive forces.

16. An electromagnetic structure comprising a frame, first and second permeable core portions generally U-shaped with first and second legs on said frame, a symmetrical armature pivotally mounted to said frame, first and second pairs of permeable feet cooperating with said first and second legs and said armature to establish first and second substantially closed magnetic circuits for one arcuate position of said armature, two feet being disposed on one side of said armature and the other two feet being disposed on the opposite side of said armature, each of said first feet being the same distance from said pivot point, each of said second feet being the same distance from said pivot point, winding means disposed on said first and second core portions, respectively, and means for energizing said winding means from an alternating current source for generally equal ampere turns at a phase displacement of at least forty-five degrees.

17. An electromagnetic structure comprising a frame, a core including first and second permeable core portions generally U-shaped with first and second legs on said frame, a permeable symmetrical armature pivotally mounted to said frame at the center of gravity of said armature, first and second pairs of permeable feet on one of said core and armature and extending toward the other thereof, two feet being disposed on one side of said armature and two feet being disposed on the opposite side of said armature, each of said first feet being the same distance from said pivot point, each of said second feet being the same distance from said pivot point, said armature in one rotational limit adapted to establish substantially closed first and second magnetic circuits through said first and second core portions of approximately equal low reluctance and for another rotational limit position adapted to establish approximately equal higher reluctance in said first and second magnetic circuits because of increased air gaps therein, first and second coils disposed on said first and second core portions, respectively, and means for energizing said coils from an alternating current source for substantially equal ampere turns at a phase displacement of substantially ninety degrees therebetween, whereby there is established a substantially con-

stant torque on said armature throughout a complete cycle of said alternating current voltage.
